UNITED STATES PATENT OFFICE.

MOSES JOHNSON, OF LOCKPORT, NEW YORK.

HAND-TRUCK.

SPECIFICATION forming part of Letters Patent No. 224,694, dated February 17, 1880.

Application filed December 15, 1879.

To all whom it may concern:

Be it known that I, MOSES JOHNSON, of the city of Lockport, in the county of Niagara, in the State of New York, have invented certain new and useful Improvements on Hand-Trucks; and I do hereby declare that the following is a full, clear, and exact description of the same.

My invention relates to an improvement in hand-trucks; and it consists in the combined clutch and support or base, the lugs *a a* and *c' c'*, the sharp points *c c* and *b b*, respectively, of the clutch and support, the bolts *a' a'*, in connection with orifices *d d*, for adjusting the length of the arms and leverage of the truck to suit the nature of the work or the strength of the operator, and in the combination and arrangement of the parts, as hereinafter more specifically set forth.

20 The drawing is a perspective view of a device embodying my invention.

The letters *A A* represent the longitudinal sides of a frame or platform, connected by the transverse bars *b' b'* and supported by the vertical standards, to which they are rigidly attached, these standards *e e* having shoulders *e' e'*, upon which rest the longitudinal side pieces. The standards furnish the bearings of the axle *g*, and the transverse bar *b''* projects through the

30 side pieces, *A A*, and standards *e e*. The longitudinal side pieces are curved to form a concave surface, the better to retain in position the article lifted or loaded upon the truck, and are pointed at their extreme ends, as shown, 35 in order the more securely to grasp or the more easily to be slipped under the article to be lifted, and their front ends are fashioned into handles, as shown at *E*. They are provided with the lugs *a a*, which are pivoted thereto by the pins *d' d'*.

When articles contained in wooden or solid packages are to be lifted the lugs are thrown back, and the weight of the article pressing upon the points *b b*, and the points of the clutch also 45 pressing thereon, are alone sufficient to grapple and secure such article upon the truck; and when the commodity to be removed is contained in sacks, bales, or such material as

would be injured by the sharp points aforesaid, the lugs *d' d'* are thrown forward to cover 50 the points, and a smooth surface is thus presented to the fabric in which such commodity is contained.

The clutch *B* is provided with the sharp points *c c*, for clutching such packages as are 55 not liable to be thus injured, and also with the lugs *c' c'*, projecting beyond said points, as a means of preventing the piercing or injury of such bag, bale, or other device as would be penetrated by them, and it is arched or curved 60 in reverse form to the longitudinal sides of the support or base *D*, thus forming a recess between the upper and lower sections of the device, the sections being bolted together, as shown. The clutch may also be bolted or projected forward beyond the sharp points of the supporting-frame by means of the bolts *a' a'* and orifices *d'' d''*. When large cases or boxes are 65 to be grappled its longitudinal pieces are also rounded or curved downward at the front to 70 form the handles *F F*, which handles, when the device is lowered, also serve as feet or standards for supporting the load.

My hand-truck is thus provided with two sets of handles, acting as levers of different 75 force, either set of which may be used at will for the intended purpose.

What I claim is—

1. The combination of the longitudinal pieces *A A*, having orifices *d d*, to adjust the 80 length of the arms by means of the bolts *a' a'*, lugs *a a*, and the clutch *B B*, having lugs *c' c'*, substantially as shown and described.

2. The combination of the longitudinal side pieces, *A A*, having handles *E E*, uprights or 85 standards *e e*, and clutch *B B*, having handles *F F* and points *c c*, substantially as herein shown and set forth.

In testimony that I claim the foregoing as my own I affix my signature in presence of 90 two witnesses.

MOSES JOHNSON.
